TAPE SERVING MACHINE

Theodore H. Krueger, Stratford, Conn.

Application November 8, 1935, Serial No. 48,840

15 Claims. (Cl. 91—14.5)

This invention relates to dispensing machines for gummed tape, and more particularly to machines of the type in which the leading end of the tape is seized by the operator and pulled forward to draw the tape across a moistening device.

It is a primary object of the present invention to provide means in a machine of this type which will avoid the necessity of the operator's putting his thumb or fingers upon moist, gummed portions of the tape, which will nevertheless moisten the tape in such a manner that the whole severed strip adheres to the package on which it is placed after severance, and which will facilitate the seizing of the leading end of the tape by the operator.

To this end it is a feature of the invention that provision is made of a tape moistener, a tape severing means normally adjacent to the moistener in position to separate the wet tape from the dry tape but moveable in anti-tape feeding direction by the same fingers of the operator with which he grasps the leading end of the dry tape, and of means for causing the exposed dry end of the tape to be deflected into such position relative to the operator's fingers that he can grasp the tape by thereafter moving only his thumb, and in such a position that when the operator allows the knife to return to its normal severing position without causing any relative movement between knife, fingers, thumb and tape, the thumb will pass over the moistening element without touching it, and the fingers will be pressing a portion of the tape firmly against the moistening brush.

Thus a tape zone containing an excess of moisture is provided between the dry end and the normally moistened length of the tape. The zone of excess moisture supplies moisture enabling the dry end to be moistened and struck down as an incident of applying and pressing the tape against a package.

Other objects and advantages will hereinafter appear.

45 In the drawings forming part of this specification,

Fig. 1 is a longitudinal view in sectional elevation through a dispensing machine embodying features of the invention, the view showing the general organization of the parts;

Fig. 2 is a sectional view taken upon the line 2—2 of Fig. 1 looking in the direction of the arrows;

Fig. 3 is a fragmentary sectional detail view 55 showing the tape deflector and moistener with

the parts of the tape deflector in a different position from that of Fig. 1;

Fig. 4 is a view similar to Fig. 3 showing the thumb moved over into tape gripping position;

Fig. 5 is a view similar to Figs. 3 and 4, but 5 showing the tape pressed by the fingers against the moistening brush;

Fig. 6 is a perspective view of a package sealed by a piece of tape drawn from the apparatus;

Fig. 7 is a view similar to Figs. 3 to 5 but showing the tape being pulled forward over the moistener;

Fig. 8 is a fragmentary view in sectional elevation illustrating a modified embodiment of the invention; and

Fig. 9 is a fragmentary view in sectional elevation illustrating a further modified embodiment.

The dispensing machine comprises a frame 1 which forms at the rear end thereof a receptacle for receiving a roll 2 of gummed tape. The receptacle is provided with a hinged cover 3 so that access may be had to the interior of the receptacle as required. The cover is adapted to be swung back to the dot and dash line position indicated at 3a in Fig. 1. An arm 4 supported upon a pivot pin 5 carries at its forward end a bar 6 having a presser strip 7 of felt or other suitable friction material mounted thereon. The felt presser strip 7 bears against a lip 8 by gravity and presses the tape 9 against the lip, thereby applying a light frictional resistance to the drawing forward of the tape, so that the tape is held taut when pulled forward, and is restrained against retrograde movement at other 35 times.

An inverted bristle brush 10 is set in a reservoir or tank 11 at the forward end of the frame 1, the butt of the brush being submerged in water. The brush is supported between the rear wall 12 40 of the reservoir 11 and a removable cover plate 13 of the reservoir. The tape is intended to be drawn from the roll 2 between the lip 8 and the presser foot 7, and across the tip of the brush 10.

Between the lip 8 and the brush 10 provision is made of a tape severing and tape deflecting device 14. The device 14 comprises arms 15 pivotally mounted upon a cross pin 16. Upon the upper ends of the arms 15 there is fixedly 50 mounted a tear-off blade and tape tensioning device 17 and an opposed guide plate 18 which jointly form a guide throat through which the tape 9 passes toward the brush in a plane substantially below the tops of the bristles and ap- 55

proximately at right angles to the direction of the bristles. The tear-off blade normally stands in the position shown in Fig. 1, so that the wet tape is separated from the dry tape, leaving only dry tape in the machine.

5 The blade 17 has an up-turned portion 19 which is adapted to be engaged by the fingers and thrust in anti-tape-feeding direction to expose the leading dry end of the tape. Such operation causes the arms 15 to be rocked counter-clockwise against the action of a retractile spring 20 which is secured at one end to the machine frame and at the opposite end to a pin 21 mounted on the tail portion of the arm 15.

10 A plate 22 carried by rocker arms 23 is pivotally supported upon the arm 15 beneath plate 18 upon a cross pin or shaft 24. The plate 22 carries a weight 25 which normally urges the plate to its lower position as indicated in Fig. 1. The 15 plate 22 is provided at its forward end with an upturned deflecting lip 26 which is located far enough forward to stand a little clear of the forward ends of the plates 17 and 18 when the plate 22 is swung counter-clockwise relative to 20 them.

15 At the conclusion of any operation the parts remain in the position shown in Fig. 1 with the forward end of the tape substantially flush with the forward edges of the plate 17.

20 When the operator desires to draw a strip of tape from the machine he places his hand in substantially the position illustrated in Fig. 1 so that one or more of his fingers bear against the plate 19 in a position to thrust it rearward. The 25 operator thrusts the plate rearward as illustrated at successive stages by Figs. 3 and 4. This carries the arm 15 counter-clockwise and the arm carries with it the deflector lip 26 and the supporting arms 23 thereof. During this movement 30 the tape 9 is restrained against retrograde movement by the lip 8 and the opposed presser strip 7 so that the tear-off blade 17 and the plate 18 move rearward relative to the tape, causing a leading end of the tape to be exposed in advance 35 of said blade and plate. The plate 18 serves as a guide to hold the tape above and clear of the lip 26, so that the lip does not engage nor obstruct the leading end of the tape.

35 The rearward swinging of the arm 25 carries 40 the tail portions of the supporting arms 23 against an abutment lip 27 formed on the frame. Continued rearward movement of the plate 19 and the arms 15 causes the plate 22 to swing counter-clockwise relative to the arms 15. As 45 shown in Fig. 4, this movement causes the lip or flange 25 to swing up across the forward ends of the plates 17 and 18 and to momentarily curve or deflect the leading end 27 of the tape upward to a position like that shown in Fig. 4.

50 The operator now moves his thumb to grip the tape against his forefinger as illustrated in dot and dash lines in Fig. 4. The operator then 55 draws the tape into engagement with the brush bristles as shown in Fig. 5, the arm 15 and the parts carried thereby being meanwhile returned to their normal positions. The operator now 60 draws the desired length of tape across the brush and tears it off against the tear-off blade 17.

65 The torn off length of tape 28 is then applied 70 to a package 29 to seal the wrapper of the package. It will be observed that a portion 30 of the deflected tape end never comes in contact with the brush and is therefore dry even after the tape has been torn off. There is a zone 75 75 of the tape, however, adjacent this dry end (the

portion shown in contact with the brush, Fig. 5) which is moistened excessively by reason of the fact that the arrangement of parts causes the fingers of the operator to press this portion 31 directly against the brush. The later moistened 5 portions of the strip are brought into a lighter contact with the brush due to tautness produced by the pull of the operator's hand from in front, and to the tensioning or dragging effect of passing the tape at a sharp (approximately 90°) 10 angle around the cutter edge 17. When the tape has been laid on the package, therefore, in the manner shown in Fig. 6, the operator in smoothing it down may draw his hand from left to right across the successive zones 31 and 30. This 15 causes the excess moisture on the zone 31 to be spread underneath the zone 30 so that the zone 30 is thus moistened and sticks to the package even though it was dry when it left the dispensing device. 20

In Fig. 8 the tape is drawn from a source of supply (not shown) over a support 8a and beneath a gravity operated presser 1a to a moistening brush 10a. So far as the operator is concerned the mode of operation is the same as that 25 of the embodiment disclosed in Figs. 1 to 5 and 7. The tape severing and tape deflecting means is different, however, in construction.

A tear-off blade 30 having an up-turned, finger engaging, operating abutment 31 is carried at 30 the upper ends of arms 32 which are pivotally mounted upon a pin 33. A spring 34 urges the blade 30 toward its normal position adjacent the moistener. A tape deflecting or bending plate 35 is pivotally mounted upon a pin 36. The pin 35 36 is supported on ears 37. A spring 38 urges the bending plate 35 counter-clockwise. An end portion of the tear-off blade, however, engages a flange of the bending plate 35 and the spring 34 is made enough stronger than the spring 38 to 40 cause the parts to remain normally in the position shown in full line in Fig. 8. The flange on the plate 35 is located outside the lateral bounds of the tape path and spaces the plate 35 from the blade 30a, so that the tape is caused to pass 45 freely between the blade and the plate.

When the operator places his fingers against the finger piece 31 of the blade 30 and pushes it rearward the blade is swung to the dot and dash line position indicated at 30a in Fig. 8. The bending plate 35 follows the tear-off blade to the dot and dash line position 35a of Fig. 8, bending the leading end of the tape upward to a position adjacent the fingers which were used for pushing the blade rearward, so that the operator can grip 55 the tape merely by moving his thumb toward these fingers. By placing the thumb against the upper end of the deflected tape so that the tip of the thumb stands above the finger tips, the thumb may be properly located so as to escape 60 engagement with the brush although the finger tips are caused to press the tape firmly against the brush. The operator is influenced by the mechanism to move his thumb and fingers in such a path since the natural tendency is simply 65 to pull forward on the tape without lifting the fingers off of the upper surface of the blade 30.

In the embodiment of Fig. 9 the tape is led from a source of supply around a roller 40 and thence between rollers 41 and 42 which are 7 mounted in the machine frame. A tear-off blade 43 having an operating finger piece 44 is mounted at the upper ends of swinging arms 45. A spring 46 connected to one of the arms 45 and to the machine frame normally holds the blade 43 for 7

ward adjacent the brush in the position shown in full lines in Fig. 9. It will be noted that the blade 43 in this position holds the tape bent forward but that the tape is not bent into a sharp angle so that it retains its natural resiliency and its tendency to return to a substantially straight line position when permitted to do so. When the tear-off blade 43 is thrust rearward the tape is restrained from moving rearward with it by the 10 roller 41 and hence the leading end of the tape is exposed by such rearward movement of the blade. When the blade has moved to the rear of the roller 42 as shown in dot and dash lines in Fig. 9 the tape springs upward to the vertical 15 position illustrated in Fig. 9, closely adjacent the fingers which the operator is using for moving the blade. The operator then moves his thumb toward these fingers in the manner already described to grip the tape, and draws the tape forward, the thumb passing clear of the brush but the fingers pressing the tape firmly against the brush.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

I claim:

1. In a tape serving machine, in combination, means for supporting a roll of tape, a moistener past which the tape may be drawn by the operator, a tear-off blade disposed between the roll support and the moistener, at a short distance below the top of the moistener, means supporting the tear-off blade for movement away from the moistener by the operator in an anti-tape-feed direction to expose the leading end of the dry tape, means automatically effective in response to such manual movement of the blade to bend the exposed leading end of the tape upward into position to be conveniently grasped by the blade moving hand of the operator, and means yieldingly urging the blade toward the moistener.

2. In a tape serving machine, in combination, means for supporting a roll of tape, a moistener past which the tape may be drawn by the operator, a tear-off blade disposed between the roll support and the moistener and normally located adjacent the moistener to enable the moistened portion of the tape to be separated from the dry portion thereof, means supporting said tear-off blade for movement by the operator to expose the leading end of the dry tape, means for bending such exposed end of the tape into position to be conveniently grasped by the operator, and means yieldingly urging the blade toward the moistener.

3. In a tape serving machine, in combination, means for supporting a roll of tape, a moistener past which the tape may be drawn by the operator, tape severing means disposed adjacent the moistener for severing the moistened tape from the dry tape so that only dry tape will remain in the machine after a severing operation, means yieldingly urging the tape severing means toward the moistener, the tape severing means being movable by the operator to expose the leading end of the dry tape after a severing operation, and means for automatically bending the leading end of the dry tape into position to be conveniently grasped by the operator after it has been so exposed.

4. In a tape serving machine, in combination, means for supporting a roll of tape, a moistener past which the tape may be drawn by the operator, a tear-off blade disposed between the roll support and the moistener and normally located adjacent the moistener to sever the moistened tape from the dry tape so that only dry tape will remain in the machine after the severing operation, means supporting the tear-off blade for movement by the operator in an anti-tape-feed direction to expose the leading end of the dry tape, a bending lip carried by the blade support adjacent the forward edge of the blade and at the opposite side of the tape path from the blade, and means for moving said bending lip across the edge of the tear-off blade to bend the exposed end of the tape around the tear-off blade into position to be conveniently grasped by the operator.

5. In a tape serving machine, in combination, means for supporting a roll of tape, a moistener past which the tape may be drawn by the operator, a tear-off blade disposed between the roll support and the moistener and normally located adjacent the moistener to sever the moistened tape from the dry tape so that only dry tape will remain in the machine after the severing operation, means supporting the tear-off blade for movement by the operator in an anti-tape-feed direction to expose the leading end of the dry tape, a bending lip carried by the blade support adjacent the forward edge of the blade and at the opposite side of the tape path from the blade, and means for moving said bending lip across the edge of the tear-off blade to bend the exposed end of the tape around the tear-off blade into position to be conveniently grasped by the operator, and means for automatically restoring the tear-off blade and the bending lip to their normal positions with the blade adjacent the moistener and the lip clear of the blade.

6. In a tape serving machine, in combination, means for supporting a roll of tape, a moistening bristle brush past which the tape may be drawn by the operator, a tear-off blade disposed between the roll support and the moistener and normally located adjacent the brush in a plane intersecting the brush at a substantial distance below the bristle tips and formed to define a path of tape movement toward the brush, means for moving the blade in anti-tape-feed direction to expose the leading end of the dry tape, and means operated by such movement of the blade to bend the exposed dry end of the tape around the edge of the tear-off blade into position to be conveniently grasped by the operator, and means yieldingly urging the blade toward the moistener.

7. In a tape serving machine, in combination, means for supporting a roll of tape, a moistener past which the tape may be drawn by the operator, a tear-off blade disposed between the roll support and the moistener and normally located adjacent the moistener to sever the moistened tape from the dry tape so that only dry tape will remain in the machine after the severing operation, means restraining the tape against retrograde movement, means supporting the tear-off blade for movement by the operator in anti-tape-feed direction to expose the leading end of the dry tape, a bending lip carried by the plate and supported at the opposite side of the tape path from the tear-off blade, an operating abutment associated with the bending lip and movable with the blade support, and means for

- intercepting said abutment as it moves rearward to cause it to move the bending lip across the edge of the tear-off blade to bend the exposed end of the tape around the edge of the tear-off blade into position to be conveniently grasped by the operator.
8. In a tape serving machine, in combination, means for supporting a roll of tape, a moistener past which the tape may be drawn by the operator, a tear-off blade disposed between the roll support and the moistener and normally located adjacent the moistener to sever the moistened tape from the dry tape so that only dry tape will remain in the machine after the severing operation, means supporting the tear-off blade for movement by the operator in anti-tape-feed direction to expose the leading end of the dry tape, a tape bending lip carried by the support, operating means for the bending lip also carried by the support, and means for engaging the lip operating means as the latter moves rearward with the tape support to project the lip across the edge of the tear-off blade to bend the tape into position to be conveniently grasped by the operator.
9. In a tape serving machine, in combination, means for supporting a roll of tape, a moistener past which the tape may be drawn by the operator, a tear-off blade disposed between the roll support and the moistener and normally located adjacent the moistener to sever the moistened tape from the dry tape so that only dry tape will remain in the machine after the severing operation, a rocking support upon which the tear-off blade is fixedly mounted, a spring connected to the support for urging the blade in tape feeding direction, means for thrusting the blade support in anti-tape-feed direction, a bending lip, a support for the bending lip pivoted on the blade support, and means for engaging the lip support as it moves rearward with the blade support to cause it to project the bending lip across the edge of the tear-off blade to bend the exposed end of the tape across the edge of the blade.
10. In a tape serving machine, in combination, means for supporting a roll of tape, a moistener past which the tape may be drawn by the operator, a tear-off blade disposed between the roll support and the moistener, means supporting the tear-off blade for movement by the operator in an anti-tape-feed direction to expose the leading end of the dry tape, means yieldingly urging the blade toward the moistener, and means automatically effective in response to such manual movement of the blade to bend the exposed leading end of the tape upward into position where the operator can grasp it by moving only his thumb and so that when the blade is allowed to return to its position of rest without any relative motion between fingers, thumb, tape and blade, the thumb and the forward end of the tape will remain dry and the finger tips will press the tape directly beneath them against the moistener.
11. In a tape serving machine, in combination, means for supporting a roll of tape, a moistener past which the tape may be drawn by the operator, a tear-off blade disposed between the roll support and the moistener, means supporting and guiding the tear-off blade for bodily movement by the operator in an anti-tape-feed direction substantially at right angles to the direction of the tear-off pull to expose the leading end of the dry tape, and means automatically

effective in response to such movement of the blade to bend the exposed leading end of the tape upward into a position substantially at right angles to the tape remaining at that moment under the tear-off blade.

12. In a tape serving machine, in combination, means for supporting a roll of tape, a moistener past which the tape may be drawn by the operator, a tear-off blade disposed between the roll support and the moistener, means supporting and guiding the tear-off blade for movement by the operator in an anti-tape-feed direction substantially at right angles to the direction of the tear-off pull to expose the leading end of the dry tape, and means automatically effective in response to such movement of the blade to bend the exposed leading end of the tape upward into a position substantially at right angles to the tape remaining at that moment under the cutter blade to extend from below the top of the moistener to above the top of the moistener, the arrangement of the elements being such that if the fingers and the thumb of the operator preserve this substantially vertical bend of the forward end of the tape as the cutter blade moves with them back to its position of rest, the extreme forward end of the tape, and the operator's thumb will remain dry, while that portion of the tape adjacent to it will be squeezed into the body of the resilient moistener by the pressure of the fingers.

13. In a tape serving machine, in combination, means for supporting a roll of tape, a moistener past which the tape may be drawn by the operator, a tear-off blade disposed between the roll support and the moistener below the top of the moistener and normally located closely adjacent the moistener; means urging the blade toward its normal position, means engageable by the fingers of the operator for moving the tear-off blade in anti-tape-feed direction to expose the leading end of the tape, and means for causing the exposed leading end of the tape to be turned upward from the position which it occupied beneath the blade into a position adjacent the fingers used for moving the blade so that it can be gripped by the operator upon movement of the thumb towards said finger.

14. In a tape serving machine, in combination, means for supporting a roll of tape, a moistener past which the tape may be drawn by the operator, a tear-off blade disposed between the roll support and the moistener and normally located closely adjacent the moistener at a short distance below the top thereof; means engageable by the fingers of the operator for moving the tear-off blade in anti-tape-feed direction substantially at right angles to the direction of the tear-off pull to expose the leading end of the tape, and means for causing the exposed leading end of the tape to be turned upward from the position which it occupied beneath the blade into a position adjacent the finger used for moving the blade to extend from below the top of the moistener to above the top of the moistener so that it can be gripped by the operator upon movement of the thumb towards said finger at a point sufficiently above the finger tip to enable the operator when drawing the gripped tape forward in tape feed direction to move his thumb in a path clear of the moistener while causing the finger to press the tape firmly against the moistener.

15. In a tape serving machine, in combination, means for supporting a roll of tape, an upstanding moistener wick across which the tape may be

drawn by the operator, a tear-off blade normally disposed between the roll support and the moistener at a short distance below the top of the moistener, means supporting the tear-off blade for movement toward and from the moistener substantially along the tape feeding path, means for urging the tear-off blade toward the moistener in tape feeding direction, and means for manually

thrusting the blade away from the moistener in anti-tape-feeding direction, comprising an abutment extending upward from the tear-off blade at a distance back from the tear-off edge of the blade substantially equal to the thickness of the 5 human finger.

THEODORE H. KRUEGER.
